DESIGN FOR A WHIRLING TOY

Dorothy M. Smith, Santa Barbara, Calif.

Application May 2, 1947, Serial No. 138,751

Term of patent 14 years

(Cl. D34—15)

To all whom it may concern:

Be it known that I, Dorothy M. Smith, a citizen of the United States, residing at 501 West Junipero Street, Santa Barbara, in the county of Santa Barbara and State of California, have invented a new, original, and ornamental Design for Whirling Toy, of which the following is a specification, reference being had to the accompanying drawing, forming part thereof.

In said drawing:

Fig. 1 is a side elevational view of a whirling toy showing my new design in a stationary position;

Fig. 2 is an elevational view of one of the pendants shown in Fig. 1;

Fig. 3 is a bottom plan view of the pendant shown in Fig. 2; and

Fig. 4 is a sectional view taken on line 4—4 in Fig. 2.

The dominant features of my design are shown in solid lines in the drawing.

I claim:

The ornamental design for a whirling toy, as shown and described.

DOROTHY M. SMITH.
